US00D918921S

(12) **United States Design Patent** (10) **Patent No.:** **US D918,921 S**
(45) **Date of Patent:** **** May 11, 2021**

(54) **HOLDER FOR A MOBILE ELECTRONIC DEVICE**

(71) Applicant: **Samsonite IP Holdings S.à.r.l.**,
Luxembourg (LU)

(72) Inventors: **Bryan Lee Hynecek**, Redwood City,
CA (US); **Mia Hutchinson**, San Mateo,
CA (US); **Joyce Kung**, San Francisco,
CA (US); **Colin Reed**, San Francisco,
CA (US); **Minna Chong**, Oakland, CA
(US); **Derrick Del Moral**, San Bruno,
CA (US)

(73) Assignee: **Samsonite IP Holdings S.à.r.l.**,
Luxembourg (LU)

(**) Term: **15 Years**

(21) Appl. No.: **29/660,567**

(22) Filed: **Aug. 21, 2018**

(51) LOC (13) Cl. **14-02**

(52) U.S. Cl.

USPC **D14/440**

(57) **CLAIM**

The ornamental design for a holder for a mobile electronic device, as shown and described.

DESCRIPTION

FIG. 1 is an upper side view of the holder for a mobile electronic device in accordance with a first embodiment of the invention.

FIG. 2 is a front view of the holder for a mobile electronic device in accordance with the first embodiment of the invention.

FIG. 3 is a left side view of the holder for a mobile electronic device in accordance with the first embodiment of the invention.

FIG. 4 is a right side view of the holder for a mobile electronic device in accordance with the first embodiment of the invention.

FIG. 5 is a lower side view of the holder for a mobile electronic device in accordance with the first embodiment of the invention.

FIG. 6 is a rear view of the holder for a mobile electronic device in accordance with the first embodiment of the invention; and,

FIG. 7 is an exploded front upper-side perspective view of the holder for a mobile electronic device in accordance with the first embodiment of the invention.

1 Claim, 6 Drawing Sheets
